RECTIFICATION BY PRECOOLING AND DIVIDING THE FEED GAS INTO PARTIAL STREAMS

BACKGROUND OF THE INVENTION

This invention relates to a process for improved rectification by precooling and dividing the precooled feed gas mixture into partial streams of high-liquid and low-liquid contents at different temperatures. More particularly, this invention relates to such rectification processes where the feed gas mixture is at a higher pressure than that of the rectifying column, and enters the column, after expansion, as a wet vapor.

It is known that rectification is accomplished more easily when the feed gas mixture, before entering the column, is divided into two partial streams of different liquid contents. This is achieved by heating one stream with a source of heat, and cooling the other stream with a source of refrigeration. Thus, the first partial stream is a wet vapor of low-liquid content and the second stream is a wet vapor of high-liquid content. The second partial stream is fed to the column a few trays above the first one.

In such process, free energy is added to the feed gas mixture by means of the aforesaid sources of heat and refrigeration.

This invention is an improvement of the process disclosed and claimed in copending Pat. application Ser. No. 775,402, filed Nov. 13, 1968, by Otto Kaiser. The process of said copending application carries out the rectification of a divided feed gas, without the necessity of adding free energy thereto, by passing in heat exchange relation an expanded partial stream of the feed gas with another partial stream before the latter is expanded.

SUMMARY OF THE INVENTION:

It is the object of this invention to carry out an improved rectifying process with a divided feed gas, without the necessity of adding free energy thereto, in which process the difference between the liquid-to-vapor ratios of the partial streams is greater than has heretofore been achieved.

A process was found for the rectification of a gas mixture, in which the feed gas mixture is divided into two partial streams of different liquid contents. The partial stream with the higher liquid content is fed to the column a few trays above the tray where the partial stream of low-liquid content is introduced. The characteristic feature of this process is that all of the feed gas stream is first precooled with the refrigeration of a precooled partial stream thereof which has been expanded, the expanded partial stream is then fed into the column, and another precooled partial stream is also expanded and fed, without giving up its refrigeration, into the column a few trays above the first partial stream.

A slight improvement of this process can be achieved by further cooling all of the precooled second partial stream with the refrigeration produced by expanding only the part of the further cooled precooled second stream remaining after a third partial stream has been divided therefrom. The expanded remainder of the further cooled precooled second stream, after transferring its refrigeration, is introduced into the column a few trays above the tray where the first partial stream enters the column, while the third partial stream is also expanded and fed, without giving up its refrigeration, into the column a few trays above the tray where the second partial stream enters the column.

In the description which follows, a two-component gas mixture is used to explain the process in detail. Of course, the process is not limited to two-component mixtures.

BRIEF DESCRIPTION OF THE DRAWINGS:

FIG. 1 shows a process diagram in which the feed gas is di-

vided into two partial streams; and

FIG. 2 shows a process diagram in which the feed gas is divided into three partial streams.

DESCRIPTION OF PREFERRED EMBODIMENT:

According to this invention, the feed gas mixture 12, as shown in FIG. 1, is precooled in heat exchanger 2 by a partial stream of the precooled feed gas which has been expanded through expansion valve 1. After passing through heat exchanger 2, the expanded first partial stream enters rectifying column 4 by way of line 3 as a wet vapor of relatively low-liquid content. The precooled second partial stream is then expanded through expansion valve 5 and introduced into rectifying column 4 by line 6 as a wet vapor of relatively high-liquid content, several trays above the tray where the first partial stream enters the column.

FIG. 2 shows the process of this invention with a division of the feed gas mixture into three partial streams. The symbols used in FIG. 2 are the same as used in FIG. 1. To begin with, the feed gas stream 12 is precooled in heat exchanger 2 and divided into two partial streams. The precooled first stream is expanded to column pressure through expansion valve 1, heated in heat exchanger 2, and fed to rectifying column 4 through line 3 as a wet vapor of low-liquid content. The precooled second partial stream is further cooled in heat exchanger 8 and then again divided into two partial streams. One of these further cooled precooled partial streams is expanded through expansion valve 7 to column pressure and thereby cooled, then somewhat heated in heat exchanger 8 and fed to rectifying column 4 through line 9, a few trays above the tray where the first partial stream is introduced. The remaining or third partial stream is further cooled by expansion through expansion valve 10 to column pressure and introduced by line 11 into column 4 as the coldest partial stream with the highest-liquid content. It is therefore fed to rectifying column 4, several trays higher than the trays where the two other partial streams enter the column.

As already mentioned, the process of this invention is an improvement of the process of copending application Ser. No. 775,402, in that the difference between the liquid contents of the partial streams of the gas mixture fed to the rectifying column has been increased by this invention. Consequently, the intersecting points of the rectification lines in the relevant McCabe-Thiele diagram are now further apart; in short, rectification has been improved.

What is claimed is:

1. In the process for the rectification of a feed gas mixture at elevated pressure, the improvement which comprises precooling said feed gas and then dividing the precooled feed gas into two partial streams of the same composition, expanding one partial stream through an expansion valve, passing the expanded partial stream in countercurrent heat exchange relation with said feed gas to effect the aforesaid precooling thereof, then introducing said expanded partial stream as a wet vapor of relatively low-liquid content into a rectification zone, further cooling and then dividing the other partial stream to provide a further cooled third partial stream, expanding the remainder of the further cooled other partial stream through an expansion valve and passing it in countercurrent heat exchange relation with said other partial stream to effect the aforesaid further cooling thereof, then introducing the expanded remainder of the further cooled other partial stream as a wet vapor of relatively high-liquid content into said rectification zone at a tray above the tray at which said wet vapor of relatively low-liquid content is introduced, and expanding said further cooled third partial stream through an expansion valve and introducing it into said rectification zone at a tray above the tray at which said wet vapor of relatively high-liquid content is introduced.
